US00D876748S

(12) United States Design Patent (10) Patent No.: US D876,748 S
Khubani (45) Date of Patent: * Mar. 3, 2020

(54) GLOVE

(71) Applicant: Hempvana, LLC, Miami Beach, FL (US)

(72) Inventor: Jahan Khubani, Saddle River, NJ (US)

(73) Assignee: HEMPVANA, LLC, Miami Beach, FL (US)

() Term: 15 Years

(21) Appl. No.: 29/695,940

(22) Filed: Jun. 24, 2019

(51) LOC (12) Cl. 16-06

(52) U.S. Cl.

USPC D2/617

(58) Field of Classification Search

USPC D2/617

CPC A41D 19/00

See application file for complete search history.

(57) CLAIM

The ornamental design for a glove, as shown and described.

DESCRIPTION

FIG. 1 is a front perspective view of a glove in accordance with the present design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof; and,

FIG. 9 is a further front perspective view thereof.

The broken line showing of a hand is included for the purpose of illustrating portions of the “article” and forms no part of the claimed design.

1 Claim, 7 Drawing Sheets
